(57) **CLAIM**

The ornamental design for a dispenser, as shown.

DESCRIPTION

FIG. 1 is a front elevation view of the first embodiment of the dispenser showing our new design;

FIG. 2 is a rear view of the design shown in FIG. 1;

FIG. 3 is a left side view of the design shown in FIG. 1;

FIG. 4 is a right side view of the design shown in FIG. 1;

FIG. 5 is a top view of the design shown in FIG. 1;

FIG. 6 is bottom view of the design shown in FIG. 1;

FIG. 7 is a back-top-left perspective view of the design shown in FIG. 1;

FIG. 8 is a front-top-right perspective view of the design shown in FIG. 1; and,

FIG. 9 is a front elevation view of a second embodiment of the dispenser showing our new design where the only difference between the first and second embodiment of the dispenser is a longer vertical dimension.
